No. 881,565.

PATENTED MAR. 10, 1908.

H. A. EVERETT & A. PARKER.
SAFETY LIMIT SWITCH.
APPLICATION FILED JULY 23, 1907.

UNITED STATES PATENT OFFICE

HENRY A. EVERETT, OF BARRINGTON, NEW JERSEY, AND ARTHUR PARKER,
OF PHILADELPHIA, PENNSYLVANIA.

SAFETY-LIMIT SWITCH.

No. 881,585.

Specification of Letters Patent.

Patented March 10, 1908.

Application filed July 23, 1907. Serial No. 385,105.

To all whom it may concern:

Be it known that we, HENRY A. EVERETT and ARTHUR PARKER, citizens of the United States, residing, respectively, at Barrington, in the county of Camden and the State of New Jersey, and of Philadelphia, in the county of Philadelphia and State of Pennsylvania, have invented certain new and useful Improvements in Safety-Limit Switches, of which the following is a specification.

Our invention relates to that class of switches that are used as protective devices and our objects are to provide a means to prevent the chain block on an electric hoist from assuming a jamming position to the structural work on said hoist, and thereby preventing the breaking of the chain or wire rope, or causing injury to the electric motor or motors or the wiring connected thereto, and to eliminate all chances of accidental loss of life due to any of the above causes.

Reference is to be had to the accompanying drawing forming part hereof, and in which will be seen the construction of our apparatus, wherein,—

Figure 1 shows a sectional elevation of the apparatus mounted upon an appropriate panel or base. Fig. 2 shows a plan view, and Fig. 3 shows a wiring diagram illustrating the circuits of either position of the switch. Fig. 4 is an elevation of an insulated pinion keyed to a screw shaft.

In the accompanying drawing in which similar numerals of reference indicate corresponding parts in the several views, the numeral 1 indicates the blade of a single pole double throw switch, 2 is the pivot point, 3 and 4 are switch clips by which the switch blade 1 engages in either position.

5 is a spiral spring surrounding the pivotal shaft 6 of the switch blade 1, one end of said spring being fastened to the switch blade and the other end to the base upon which the switch is mounted. This spring upon reacting causes the switch blade 1 to engage with the clip 4.

7 is a spiral extension spring which accomplishes the same result as spring 5.

22 is a suitable base upon which the apparatus is mounted.

8 is a pin rigidly attached to the switch blade 1.

9 is a dog or finger pivoted at 10 and adapted to engage with the pin 8.

13 is a screw actuated by the pinions 14 and 15.

15 is one of the pinions in a hoisting train of gears. The pinion 14 is insulated by the insulation 30 and keyed to the shaft by the key 31.

11 is a carrier which engages with the screw 13.

12 is a guide rod which serves as a guide for the carrier 11.

16 and 17 are end bearings for the screw 13 and the guide rod 12 and also upon which the base 22 is mounted and made adjustable in a position relative to the carrier 11.

18 is a motor controlling the aforesaid train of gears for the hoisting apparatus.

19 is the field winding for the said motor.

20 is the hoisting side of the controller and 21 the lowering side.

23, 24, 25, 26, 27, 28 and 29 are leads connecting the controller, motor, motor field winding and safety limit switch.

The foregoing apparatus is suitably proportioned and mounted on an appropriate panel, all of which will be readily understood by those skilled in the art to which this invention relates.

Its mode of operation will be substantially as follows: In mesh with or actuated by one of the gears or pinions in a train of gearing for an electric hoist, the insulated pinion 14 is placed.

The pinion 14 and the screw 13 are so proportioned that the extreme travel of the chain block will move the carrier 11 a somewhat less distance than that between the finger 9 and the end bearing 16.

The switch blade being forced into engagement, against the springs 5 and 7, with clip 3 and held therein by the finger 9 engaging with the pin 8. After the chain block has assumed a predetermined position the carrier 11 is set so as any further hoisting movement will cause the carrier 11 to engage with the finger 9.

From Fig. 3 it will be seen that a lowering or hoisting movement of the chain block can be accomplished, the circuits being substantially as follows; for hoisting, positive lead 29 by controller to lead 28, safety switch blade 1, lead 25 armature 18, lead 26, by controller to lead 27, field winding 19 and lead 24 to negative line.

For lowering, positive lead 29, by controller to lead 26, armature 18, lead 25, safety switch blade 1, lead 28, by controller to lead 27, field winding 19 and lead 24 to negative line.

For lowering, positive lead 29, by controller to lead 26, armature 18, lead 25, safety switch blade 1, lead 28, by controller to lead 27, field winding 19 and lead 24 to negative line.

line. It is obvious that the position of the carrier 11 depends upon the position of the chain block. Assuming the chain block to have normal travel the carrier 11 will travel forward and backward between the end bearing 16 and the finger 9, the hoisting motion of the chain block actuates the carrier 11 toward the finger 9. When the chain block raises sufficiently high to assume the aforesaid predetermined position the carrier 11 and finger 9 engage and a further hoisting of the chain block will cause the carrier 11 to actuate and revolve finger 9 upon its pivot 10, and thereby releasing the pin 8. The spring 5 then reacts, augmented by the spring 7 thereby causing a quick disengagement of switch blade 1 and clip 3. The reaction of the springs are with such force as to cause the switch blade 1 to engage with the clip 4. It will be seen from Fig. 3 that only a lowering motion can be accomplished which will be substantially as follows, positive lead 29, by controller to lead 26, armature 18, lead 25, switch blade 1, lead 23, field winding 19 and lead 24 to negative line. In order to accomplish a hoisting motion the switch blade will have to reengage with the clip 3. If the chain block is not lowered from the aforesaid extreme hoisting position it will be impossible for the finger 9 to engage with the pin 8 due to the relative position and engagement of carrier 11 and finger 9. It will be seen that after a lowering of the chain block has been accomplished the switch blade 1 can then be held into engagement with the clip 3.

The foregoing movements accomplish the hereinbefore mentioned object of our said invention.

Having thus described the nature and object of our said invention and what we claim as new and desire to secure by Letters Patent, are—

1. In a limit switch of the character described the combination of an insulated pinion and a screw keyed to same and bearings for said screw and a carrier threaded and adapted to traverse the said screw and to engage with a hereinafter mentioned dog or finger, and a guide for the said carrier, a switching mechanism mounted on a base over the said screw, a finger or dog passing through and pivoted on said base and adapted to hold said switching mechanism in normal position, and a spring provided to actuate said switching mechanism upon the disengagement of said dog or finger with said switching mechanism, all substantially as and for the purpose shown and described.

2. In a limit switch of the character described the combination of an insulated pinion and a screw keyed to same, and bearings for said screw and a carrier threaded and adapted to traverse the said screw and also to engage with a hereinafter mentioned finger or dog upon a predetermined move-

ment of said dog or finger, and a guide for said screw and passing through said carrier, a single pole double throw switch mounted on a base over the said screw and carrier, a finger extending through and pivoted on said base, a pin on the blade of said switch and adapted to engage with said finger or dog in the normal position of said switch, and a spring opposing the engagement of the switch blade with the normal switch clip, and actuating the said switch upon the disengagement of the said finger or dog with said pin, all substantially as and for the purpose shown and described.

3. In a limit switch of the character described, an insulated pinion actuated by a gear in a train of gears, a screw secured to said pinion, bearings provided for said screw, a carrier actuated by said screw, a guide for said carrier and passing through same, a switching mechanism mounted on a base over said screw, and a finger or dog holding said switching mechanism in normal position and adapted to engage with the said carrier upon a predetermined movement of said carrier, all substantially as and for the purpose shown and described.

4. In a limit switch of the character described, an insulated pinion, said pinion meshing with a train of gears of a hoisting motion, a screw provided with bearings, said screw keyed to said insulated pinion, a carrier, said carrier threaded and adapted to traverse said screw, a guide for said carrier, a switching mechanism mounted on a base over the said carrier, a finger or dog extending through and pivoted on said base and adapted to engage with said switching mechanism in its normal position and also with said carrier upon a predetermined movement of same, and a spring opposing the engagement of said switching mechanism in its normal position, and actuating the switching mechanism upon the disengagement of said finger with said switching mechanism, all substantially as and for the purpose shown and described.

5. In a limit switch of the character described, an insulated pinion actuated by a gear in a train of hoisting gears, a screw secured to said pinion, bearings provided for said screw, a carrier threaded and adapted to traverse the said screw, a guide for said carrier and passing through same, a switching mechanism mounted on a base over said screw, and a finger or dog pivoted at said base and holding said switching mechanism in normal position, said finger or dog adapted to engage with said carrier upon a predetermined movement of said carrier, all substantially as and for the purpose shown and described.

6. In a limit switch of the character described, an insulated pinion, said pinion meshing with a gear in a train of hoisting

gears, a screw provided with bearings, said screw secured to said insulated pinion, a carrier, said carrier threaded and adapted to traverse the said screw, a guide parallel to 5 said screw and passing through the upper portion of said carrier, a switching mechanism mounted on a base over said carrier, a finger or dog extending through said base and pivoted thereon and adapted to engage 10 with said switching mechanism in its normal position and also with said carrier upon a predetermined movement of same, and a spring opposing the engagement of said switching mechanism in its normal position 15 and actuating same upon the disengagement of said finger or dog with said switching mechanism all substantially as and for the purpose shown and described.

7. In a limit switch of the character described, 20 an insulated pinion, said pinion meshing with a gear in a train of hoisting gears, a screw provided with bearings, said screw keyed to said insulated pinion, a carrier, said carrier threaded and adapted to 25 traverse the said screw, a guide parallel to said screw and passing through the upper portion of said carrier, a single pole double throw switch mounted on a base over the said carrier, a finger extending through said base, a pin on the blade of the aforesaid switch and adapted to engage with the aforesaid finger upon the normal position of said switch, and also engaging with the aforesaid carrier upon a predetermined movement of 30 said carrier, and a spring opposing the engagement of the switch blade with the normal 35 switch clip, and actuating the aforesaid switch upon the disengagement of the aforesaid finger with the aforesaid pin in the blade of the aforesaid switch, all substantially as and for the purpose shown and described. 40

said switch upon a disengagement of said switch with said finger, all substantially as and for the purpose shown and described. 45

8. In a limit switch of the character described, an insulated pinion, said pinion meshing with a gear in a train of hoisting 50 gears, a screw provided with bearings, said screw keyed to said insulated pinion, a carrier, said carrier threaded and adapted to traverse the said screw, a guide parallel to said screw and passing through the upper 55 portion of said carrier, a single pole double throw switch mounted on a base over the said carrier, a finger extending through said base, a pin on the blade of the aforesaid switch and adapted to engage with the aforesaid finger upon the normal position of said switch, and also engaging with the aforesaid carrier upon a predetermined movement of 60 said carrier, and a spring opposing the engagement of the switch blade with the normal switch clip, and actuating the aforesaid switch upon the disengagement of the aforesaid finger with the aforesaid pin in the blade of the aforesaid switch, all substantially as and for the purpose shown and described. 65

In testimony whereof we have signed our respective names to this specification in the presence of two subscribing witnesses.
